STARTING AND STOPPING POWER
TRANSMISSION MECHANISM

Abraham S. Sheroff, Boston, Mass.

Application December 14, 1943, Serial No. 514,193

3 Claims. (Cl. 192—18)

The present invention pertains generally to starting and stopping power transmission mechanisms for transmitting power to power driven machines, more particularly to starting and stopping power transmission mechanisms which can be connected directly to sewing machines for transmitting power to such sewing machines, and most specifically to starting and stopping power transmission mechanisms directly connected to, and capable of starting and stopping instantaneously, such sewing machines.

The principal object of the present invention is to provide a power transmission mechanism for interposition between a sewing machine and a source of power delivered rotationally, such, for example, as an electric motor, by the use of which power transmission mechanism the sewing machine can be set into operation at full speed and can thereafter be halted to a dead stop within a cycle of its operation, i. e., within the formation of a stitch.

Another object of the present invention is to provide a power transmission mechanism for interposition between a sewing machine and a source of power delivered rotationally, such, for example, as an electric motor, that can be so interposed without reconstructing either the sewing machine or the electric motor.

Another object of the present invention is to provide a power transmission mechanism for interposition, between a sewing machine and a source of power delivered rotationally, such, for example, as an electric motor, whose motion arresting mechanism will function automatically upon disengagement of its motion establishing mechanism.

Another object of the present invention is to provide a power transmission mechanism for interposition between a sewing machine and a source of power delivered rotationally, such, for example, as an electric motor, whose motion establishing mechanism and motion arresting mechanism are susceptible of positive control at all times by the user of the sewing machine.

Another object of the present invention is to provide a power transmission mechanism for interposition between a sewing machine and a source of power delivered rotationally, such, for example, as an electric motor, whose motion establishing mechanism and motion arresting mechanism are so susceptible of positive control at all times by the user of the sewing machine that the user of the sewing machine can, by skillful "riding of the treadle," operate the sewing machine at speeds far below its normal operat-

ing speed, and thus can execute stitching along highly inflected curves and around corners unexecutable at the normal operating speed of the sewing machine.

Another object of the present invention is to provide a power transmission mechanism for interposition between a sewing machine and a source of power delivered rotationally, such, for example, as an electric motor, which is simple in construction and inexpensive to manufacture.

These and other objects of the present invention and the advantages attendant upon its utilization will become obvious from an examination of the following description, together with the accompanying drawing, thereof, wherein:

Fig. 1 is a plan view of the present invention with the cover of the housing of the gear wheels removed.

Fig. 2 is a vertical elevation in section of the present invention taken along the line 2, 2, of Fig. 1.

In the drawing, 1 is the sewing machine, shown in part just sufficient to establish the relationship of the present invention thereunto, 2 is its handwheel, 3 is a connecting member secured rigidly to, concentrically with, and perpendicular to the plane of, the handwheel 2, connecting the handwheel 2 by means of the coupling 4 to the gear wheel 5, the smaller of the two gear wheels 25 in the housing 6, the gear wheel 5 being mounted upon and keyed to the axle 7 turning in bearings inset into the walls of the housing 6 and restrained against longitudinal movement by the collars 8, 8, secured thereto. Meshed with the gear wheel 5 is a larger gear wheel 9 mounted upon and keyed to a hollow axle 10 turning in bearings inset into the walls of the housing 6 and restrained against longitudinal movement by the collars 11, 11, secured thereto and passing 30 through the wall of the housing 6 to terminate in the bifurcation effected by the slots 12, 12. Mounted upon and secured to the hollow axle 10 is an outside collar 13 to serve as one abutment for an expansive spring. Contained by and movable longitudinally within the hollow axle 10 is an inner axle 14 upon which is mounted and to which is secured the collar 15 provided with the tongues 16, 16, received by and movable longitudinally in the slots 12, 12, in the hollow axle 10, the collar 15 being adjustable longitudinally along the inner axle 14 and securable thereto by the pin 17. Upon the inner axle 14 is mounted also the collar 18 provided with the flange 19 to serve as the other abutment for the expansive spring, the collar 18 being adjustable longitudi-

dinarily along the inner axle 14 and securable thereto by the pin 20, so that the expansive spring 21 mounted upon and encircling the inner axle 14 can be subjected to varied degrees of constraint between the two abutments 13 and 19. Suitably secured to the housing 6 by the bell crank lever support 23 is the bell crank lever 22 to which is secured the rigid rod 24 connecting it with a treadle (not shown) operable by the user of the sewing machine, the action arm of the bell crank lever 22 being either merely in contact with one end of the inner axle 14 (as shown) or actually tied to that end of the inner axle 14 by means of a suitable ball and socket joint. Upon the other end of the inner axle 14 is mounted and secured a rotatable member 25, herein shown as a wheel but not to be limited in any way to this form of construction, whose functions are to serve as a motion establishing element and a motion arresting element. As shown herein, the rotatable member 25 is provided with friction materials 26, 26, mounted upon the inner surface of the rotatable member 25 near its periphery, the one friction material engageable with the frusto-conical braking surface of the braking member 27 mounted upon the side of the housing 6 concentrically with and perpendicular to the inner axle 14, and the other friction material engageable with the frusto-conical clutch surface of the clutch member 28 mounted upon and secured to the axle 29 of the electric motor 30 concentrically with and perpendicular to both the axle 29 of the electric motor 30 and the inner axle 14. The rotatable member 25 should be of design and construction such as to possess the minimum moment of inertia, and the contacting surfaces of the friction materials should be disposed upon the rotatable member 25 as near to its periphery as is compatible with the realization of the optimum of contacting surfaces of the friction materials, the optimum of contacting surfaces of the friction materials being determined by the maximum of contacting surfaces of the friction materials engageable and disengageable in the minimum of time.

The operation of the present invention is as follows: the user of the sewing machine inserts the work into the sewing machine, and, by pressing his foot down upon the treadle, actuates the rigid rod 24 secured to the bell crank lever 22 whose action arm then displaces the inner axle 14 longitudinally within the hollow axle 10 against the pressure exerted by the expansive spring 21 upon its abutments 13 and 19 and communicated to the inner axle 14 until the friction material 26 of the rotatable member 25 comes into frictional engagement with the frusto-conical clutch surface of the frusto-conical clutch member 28 mounted concentrically and perpendicularly upon, secured to, and rotatable by, the axle 29 of the electric motor 30; whereupon the rotatable member 25 is instantaneously set into motion, which motion is communicated to the larger gear wheel 9 by means of the collar 15 secured to the inner axle 14 by the pin 17, the tongues 16, 16, of the collar 15 being received by and movable longitudinally in the slots 12, 12, in the hollow axle 10 upon which the larger gear wheel 9 is mounted and to which it is keyed. Since the larger gear wheel 9 is meshed with the smaller gear wheel 5 and since the transmission of power from the smaller gear wheel 5 to the sewing machine 1 is direct, the transmission of power from the electric motor 30 to the sewing

machine 1 is effected instantaneously. As soon as the user of the sewing machine desires to stop the operation of the sewing machine, the user of the sewing machine releases the treadle, and the expansive spring 21, which has been the more strongly compressed between the abutments 13 and 19 during the engagement of the frusto-conical clutch surface of the frusto-conical clutch member 28 with the friction material 26 upon the rotatable member 25, impels the inner axle 14 longitudinally to disengage the frictional material 26 of the rotatable member 25 from the frusto-conical clutch surface of the frusto-conical clutch member 28 and to engage the frictional material 26 of the rotatable member 25 with the frusto-conical braking surface of the frusto-conical braking member 27 mounted upon the side of the housing 6 concentrically with and perpendicular to the inner axle 14, the engagement whereof halts the operation of the sewing machine instantaneously. If, however, the user of the sewing machine desires to operate the sewing machine at speeds somewhat less than the normal operating speed of the sewing machine, in order to execute stitching along highly inflected curves and around corners unexecutable at the normal operating speed of the sewing machine, the user of the sewing machine can do so by "riding the treadle," i. e., by jiggling his foot upon the treadle in a rapid manner so that the friction materials 26, 26, of the rotatable member 25 make intermittent and successively alternative contacts with the frusto-conical clutch surface of the frusto-conical clutch member 28 and the frusto-conical braking surface of the frusto-conical braking member 27; with a little practice, the user of the sewing machine can execute stitching at relatively constant speeds varying from zero to the normal operating speed of the sewing machine.

While no small part of the success attendant upon the utilization and functioning of the present invention is due to the inertial effect of the presence of gear wheels in the train of mechanisms and the direct connection of the stopping and starting power transmission mechanism with the power driven machine, what is perhaps the chief factor in the realization of the objects of the present invention is the ensemble of the collar 13 and the flange 19 of the collar 18, both serving as abutments for the expansive spring 21, and the expansive spring 21, constrained between these two abutments 13 and 19 and rotatable with the hollow axle 10, whereby longitudinal movement of the inner axle 14 can be effected in either of two directions during the rotation of the hollow axle 10 without the development of frictional forces in planes perpendicular to the longitudinal axis of the inner axle 14 between the collar 13, the flange 19, and the expansive spring 21.

It is obvious that drastic changes may be made in the embodiment of the present invention herein presented without departing from the spirit of the present invention. In particular, the clutch means and the braking means are susceptible of great alteration within the spirit of the present invention. Hence the present invention is not to be regarded as defined by the embodiment thereof presented, but by the scopes of the claims therefor appended.

Having thus described my invention, I claim:

1. In a stopping and starting power transmission mechanism interposed between and in combination with a power driven machine and a

source of power delivered rotationally, the combination of a train of gear wheels within a housing, connecting means connecting positively one of the gear wheels with the power driven machine, a hollow axle carrying a second gear wheel secured thereto and provided at one of its ends with bifurcating slots, a collar secured upon the hollow axle, an inner axle displaceable longitudinally within the hollow axle, a second collar secured upon the inner axle and provided with tongues receivable and displaceable longitudinally in the bifurcating slots of the hollow axle, a third collar secured upon the inner axle, a rotatable member carried by and secured to the inner axle at its other end, braking means distributed between the rotatable member and the housing of the gear wheels, and an expansive spring encircling the hollow axle and the inner axle and constrained between the first collar and the third collar for maintaining in engagement the braking means.

2. In a starting and stopping power transmission mechanism interposed between and in combination with a power driven machine and a source of power delivered rotationally, the combination of a train of gear wheels, connecting means connecting positively one of the gear wheels with the power driven machine, a hollow axle carrying a second gear wheel secured thereto and provided at one of its ends with bifurcating slots, a collar secured upon the hollow axle, an inner axle displaceable longitudinally within the hollow axle, a second collar secured upon the inner axle and provided with tongues receivable and displaceable longitudinally in the bifurcating slots of the hollow axle, a third collar secured upon the inner axle, an expansive spring encircling the hollow axle and the inner axle and constrained between the first collar and the third

collar, a rotatable member carried by and secured to the inner axle at its other end, clutch means distributed between the rotatable member and the source of power delivered rotationally, and means operable by the user of the power driven machine for displacing the inner axle longitudinally to engage the rotatable member with the source of power delivered rotationally.

3. In a starting and stopping power transmission mechanism interposed between and in combination with a power driven machine and a source of power delivered rotationally, the combination of a train of gear wheels within a housing, connecting means connecting positively one of the gear wheels with the power driven machine, a hollow axle carrying a second gear wheel secured thereto and provided at one of its ends with bifurcating slots, a collar secured upon the hollow axle, an inner axle displaceable longitudinally within the hollow axle, a second collar secured upon the inner axle and provided with tongues receivable and displaceable longitudinally in the bifurcating slots of the hollow axle, a third collar secured upon the inner axle, a rotatable member carried by and secured to the inner axle at its other end, clutch means distributed between the rotatable member and the source of power delivered rotationally, braking means distributed between the rotatable member and the housing of the gear wheels, an expansive spring encircling the hollow axle and the inner axle and constrained between the first collar and the third collar for maintaining the braking means in engagement, and means operable by the user of the power driven machine to engage and disengage the clutch means and the braking means.
